UNITED STATES PATENT OFFICE.

HENRY THOMPSON AND STANLEY H. THOMPSON, OF MALVERN, MELBOURNE,
VICTORIA, AUSTRALIA.

CONCRETE AND LIKE BUILDING CONSTRUCTION.

1,384,003.

Specification of Letters Patent.

Patented July 5, 1921.

Application filed April 26, 1921. Serial No. 464,681.

To all whom it may concern:

Be it known that we, HENRY THOMPSON and STANLEY HOPE THOMPSON, both subjects of the King of Great Britain and Ireland, and residents of the city of Malvern, a suburb of the city of Melbourne, in the county of Bourke, State of Victoria, Commonwealth of Australia, (whose post-office address is 52 Wheatland road, in the said city of Malvern), have invented certain new and useful Improvements in Concrete and like Building Construction, for which we have filed an application in Australia, March 5, 1920, of which the following is a specification.

This invention relates to the construction of walls and other parts of concrete and like buildings. Its object is to provide a cheap, simple and efficient method of quickly erecting such structures from a series of standardized interlocking units, the slabs forming the inner and outer sections of a double wall being spaced apart and locked together by vertical locking bars of special shape which are adapted to slide into vertical fish-tail grooves on the slabs and bridge the air space between the inner and outer wall sections. In combination with the foregoing the slabs are provided at their ends with superimposed horizontal dovetail tongues and grooves which are adapted to interlock with corresponding tongues and grooves on the ends of adjoining slabs thereby providing, in conjunction with the aforesaid locking bars, a combined lock which effectively secures the various parts together in their proper relative positions. The features of the invention will, however, be more fully set forth in the following description and defined in the appended claims.

Referring to the drawings which form part of this specification:—

Figure 1 is a sectional plan of portion of a building showing right and left hand corners and intermediate straight portions of an external wall in accordance with the invention.

Fig. 2 is a side elevation of Fig. 1.

Fig. 3 is a sectional plan showing a corner and straight portions of an internal wall or partition and the junction thereof with an external wall in accordance with the invention.

Fig. 4 shows in sectional plan details of

the wall construction to form reveals and 55 jambs for door and window openings.

Fig. 5 is a perspective view of a corner and straight portions of a wall constructed in accordance with the invention.

Fig. 6 is an elevation of the parts seen in 60 Fig. 4.

In the drawings A indicates the concrete or like slabs which are thickened at one or both ends as shown to take half fish-tail grooves Y which extend vertically from top 65 to bottom of the slab and are adapted to slidably receive appropriate shaped portions of vertical locking bars L. These locking bars are provided at each corner with longitudinal lips or flanges F which correspond 70 to and engage within the grooves Y as shown. The inner or opposed faces of said flanges are beveled or inclined as shown, the flanges thus greatly strengthening the locking bars in the direction of their transverse 75 or lesser cross sectional dimension and enabling them to effectively withstand the stresses caused by long column bending action common to such structures.

In combination with the foregoing the 80 slabs A are provided at their ends with horizontal dovetail tongues X and grooves Z which interengage with corresponding tongues and grooves on the ends of adjoining slabs, both at corners and junctions and 85 in straight portions of walls as shown. When the tongues and grooves X, Z, are engaged as aforesaid the half fish-tail grooves Y (which are offset sidewardly from the tongues and grooves X, Z as shown) are simultaneously brought into position to form 90 full fish-tail grooves for the reception of the vertical locking bars L. These locking bars are formed in sections which are slid down into the grooves Y, the upper and lower 95 ends of each section being disposed approximately midway between the upper and lower edges of each tier of slabs as at J so that the locking bars form a bond across the horizontal joints between the slabs. These latter 100 joints as well as the vertical interlocking joints formed by the tongues and grooves X, Z and the joints J between the ends of the superimposed sections of the locking bars are all preferably grouted with cement. The locking bars thus form 105 continuous columns in the assembled structure.

The locking bars are also provided with

transverse air passages P which connect the air spaces between the inner and outer slabs and form a continuous air passage around the wall.

- 5 To form the reveals and jambs for door and window openings the horizontal tongues and grooves X, Z are omitted and the extremities of the slabs are returned at right angles for half the thickness of the slabs 10 as at R in Figs. 4 and 6 thereby forming full fish-tail grooves instead of half fish-tail grooves to accommodate the vertical locking bars L. The full fish-tail grooves extend from top to bottom of the opening 15 thus formed in the wall, the half fish-tail grooves and interlocking formation X, Z being continued beyond such opening as in Fig. 6.

By the provision of the combined lock 20 afforded by the engagement of the parts L, Y and X, Z and the thickening of the slabs to take the grooves Y as above described great strength is imparted to the walls and a highly efficient, simple and inexpensive 25 construction is provided.

Having now described our invention what we claim as new and desire to secure by Letters Patent is:—

1. A building slab having at each end 30 horizontally disposed dove-tail tongues and grooves adapted to interengage with corresponding tongues and grooves in the ends of adjoining slabs to lock the slabs together in a longitudinal direction and a thickened 35 portion projecting from one side of the slab adjacent its end or ends and forming a vertical half fish-tail groove which is offset

sidewardly from the first named tongues and grooves, for the purpose specified.

2. A building slab formed at each end 40 with complementary interlocking edge portions, whereby it may interlock with the meeting ends of adjacent slabs, said slab being further formed on the inner surface adjacent the respective ends with thickened 45 portions shaped to provide half dove-tail grooves.

3. A wall structure comprising an inner wall section and an outer wall section, each wall section being formed of a plurality of 50 slabs arranged end to end, each end of each slab being formed with interlocking means coöperating to interlock the meeting ends of the slabs, the respective slabs being formed on their inner surfaces adjacent their ends 55 to provide dove-tail grooves, and locking bars engaging the dove-tail grooves of opposing wall sections, said bars being formed with openings therethrough.

4. A wall section made up of an inner and 60 outer series of slabs, the slabs of one series being interlocked one with another at their meeting ends, and means for interlocking the slabs of the outer series with the slabs of the inner series in line with the meeting 65 ends of said slabs, whereby the slabs are interlocked in all directions.

In testimony whereof we affix our signatures.

H. THOMPSON.
STANLEY H. THOMPSON.
